(57) **CLAIM**

The ornamental design for a firearm holster adapter, as shown and described.

DESCRIPTION

FIG. 1 is a top isometric view of a first embodiment of a firearm holster adapter;

FIG. 2 is a bottom isometric view of the firearm holster adapter shown in FIG. 1;

FIG. 3 is a front side elevational view of the firearm holster adapter shown in FIG. 1;

FIG. 4 is a right side elevational view of the firearm holster adapter shown in FIG. 1;

FIG. 5 is a left side elevational view of the firearm holster adapter shown in FIG. 1;

FIG. 6 is a rear side elevational view of the firearm holster adapter shown in FIG. 1;

FIG. 7 is a top plan view of the firearm holster adapter shown in FIG. 1;

FIG. 8 is a bottom plan view of the firearm holster adapter shown in FIG. 1;

FIG. 9 is a top isometric view of a second embodiment of a firearm holster adapter;

FIG. 10 is a bottom isometric view of the firearm holster adapter shown in FIG. 9;

FIG. 11 is a front side elevational view of the firearm holster adapter shown in FIG. 9;

FIG. 12 is a right side elevational view of the firearm holster adapter shown in FIG. 9;

FIG. 13 is a left side elevational view of the firearm holster adapter shown in FIG. 9;

FIG. 14 is a rear side elevational view of the firearm holster adapter shown in FIG. 9;

FIG. 15 is a top plan view of the firearm holster adapter shown in FIG. 9; and,

FIG. 16 is a bottom plan view of the firearm holster adapter shown in FIG. 9.

(Continued)

The broken lines represent portions of the firearm holster adapter that form no part of the claimed design.
